CLAIM

The ornamental design for a wood chip soaker, as shown and described.

DESCRIPTION

FIG. 1 is a top perspective view of a wood chip soaker showing our new design;

FIG. 2 is another top perspective view thereof showing the wood chip baskets exploded from the base container of the wood chip soaker;

FIG. 3 is a top plan view of the base container of the wood chip soaker, shown without the wood chip baskets for ease of illustration;

FIG. 4 is a side elevational view thereof, the other side being a mirror image;

FIG. 5 is a front elevational view thereof; the rear being and mirror image;

FIG. 6 is a top plan view of one of the wood chip baskets shown in FIGS. 1 and 2, shown without the base container for ease of illustration;

FIG. 7 is a side elevational view thereof, the other side being a mirror image;

FIG. 8 is a bottom plan view thereof; and,

FIG. 9 end elevational view thereof, the other end being a mirror image.
